(57) **CLAIM**

The ornamental design for exhibition stand for vehicles, as shown and described.

DESCRIPTION

1. Exhibition stand for vehicles
Figure 1.1 is a perspective view of an exhibition stand for vehicles;
Figure 1.2 is a front view thereof;
Figure 1.3 is a rear view thereof;
Figure 1.4 is a left view thereof;
Figure 1.5 is a right view thereof;
Figure 1.6 is a top view thereof;
Figure 1.7 is a bottom view thereof; and
Figure 1.8 is a perspective view thereof showing an alternate condition of use.
The broken lines shown in FIGS. 1.1, 1.6 and 1.8 illustrate portions of the exhibition stand for vehicles that form no part of the claimed design.

1 Claim, 8 Drawing Sheets
